UNITED STATES PATENT OFFICE.

BORIS B. HOPPE, OF KEW GARDENS, NEW YORK, ASSIGNOR TO OLGA I. HOPPE, OF KEW GARDENS, NEW YORK.

CLASP.

Application filed May 26, 1925. Serial No. 32,877.

My present invention relates to a clasp for securing and retaining the ends of shoe strings, although it is susceptible of other applications. In particular my invention relates to improvements in, and modifications of the clasp described in the United States Patent to Olga I. Hoppe, No. 1,439,241, granted December 19, 1922. It is a further aim of my invention to provide a clasp which shall not only secure the ends of a shoe string or lace but which shall also serve to hold the tongue of the shoe in place and prevent it from working around to one side of the shoe.

My invention will be best understood from the following detailed description taken with the annexed drawings, in which:

Figure 1 is a perspective view showing a clasp of my invention applied to a laced shoe and concealing the ends of the shoe string.

Figure 2 is a somewhat enlarged view, in longitudinal section of a preferred embodiment of my invention.

Figure 3 is a view in section taken along line 3—3 of Figure 2.

Figure 4 is an enlarged view in longitudinal section of a modification, the section being taken along line 4—4 of Figure 5.

Figure 5 is a view in section taken along line 5—5 of Figure 4.

Figure 6 is a sectional view taken along line 6—6 of Figure 4.

Figure 7 is a view in longitudinal section of the device shown in Figure 4 showing the arrangement of parts when the clasp is partially open and corresponds to a section taken along line 7—7 of Figure 5.

Figure 8 is a view in longitudinal section of a further modification.

Figure 9 is a view in section taken along line 9—9 of Figure 8; and

Figure 10 is a view in section taken along line 10—10 of Figure 9 parts being broken away.

Referring to Figs. 1, 2 and 3, 10 denotes a portion of the shoe-upper having a tongue 11 to which my improved device is secured suitably by means of prongs 12 and 13 which are inserted through tongue 11, and bent upward as shown. My improved device comprises a cover member 14 attached to a base member 15 by means of a pivot 16 journaled in ears 17 attached thereto. Cover

member 14 is provided with an interior portion 18 of cam shape and preferably corrugated as shown. An upstanding member 19, preferably also corrugated, attached to or integral with base member 15 is disposed opposite cam shaped portion 18 of cover 14, whereby said opposing members 18 and 19 serve to grip and securely bind the end portions of laces 20. As will be evident from the various figures, cam shaped member 18 is of such shape that the laces may be gripped when the cover 14 is in a partly or semi-open position. However, when cover 14 is brought to a fully open position, as for example as indicated by the dotted lines in Figure 4, ample space is provided for the insertion of the laces. By causing the gripping members 18 and 19 to bind when the cover is in a semi-closed position it will be apparent that the laces may be gripped and opportunity given for inserting the loose ends of the lace beneath the cover 14.

The cover will be held closed due to the binding action on the end portions of the lace; however, to insure the cover remaining in such closed position, I preferably provide a slightly hooked shaped tip 21 at the end of cover 14 which engages a lip or catch 22 of base member 15, the spring action of both members maintaining the cover 14 shut, but permitting it to open upon the application of sufficient force by the fingers. Ears 17 are preferably provided with longitudinal portions 23, 23 which extend across the space between opposing gripping members 18 and 19 on either side of said members. These portions 23, 23 serve as a support for the laces and prevent them from being carried beneath member 18 where the gripping action is less effective.

When it is desired to employ my improved device above described for securing the ends of a shoe lace, the clasp is secured to the tongue 11 of the shoe as has been described. Cover 14 now having been moved into a fully open position, the end portions of the shoe string are inserted between the opposing gripping members 18 and 19. This having been done, the laces are gripped by moving cover 14 downward until the laces are engaged. The ends of the shoe lace may, if desired, be tied around upstanding member 19 or such tying may be dispensed with, and in either case the loose ends folded, rolled or

twisted into condensed form and inserted beneath cover 14, after which the cover is brought down and into engagement with the securing member 22 attached to base member 15. The operation in removing the clasp is substantially the reverse of the above described operation.

The above device, while effectively accomplishing the purpose for which it is designed, is nevertheless susceptible to further modifications and refinements, and in the following figures I have disclosed certain modifications possessing many desirable features. Thus in the form shown in Figs. 4, 5, 6 and 7, as well as in that shown in the remaining figures, I have provided what I term an intermediate member, which forms with the cover member a housing for more or less completely enclosing the loose ends of the lace. I also provide means whereby such member is automatically moved into the desired position and maintained in such position while the compacted ends are received between it and the cover member. Upon further downward movement of the cover, the intermediate member is moved downward therewith and is entirely contained within the cover member when the latter is in the closed position.

This intermediate member I have designated as 25 and it is pivotally secured to base member 15' by means of pivots 26 passing through upstanding portions or ears 17' of the base member 15' and extending fingers 27 of intermediate member 25, as is best shown in Figs. 5 and 6.

As shown in Fig. 5, intermediate member 25 has a cut out portion near pivots 26 for accommodating the upstanding or gripping member 19' while its other end engages beneath a hook 28 of cover 14', when the latter is in the closed position. However, when the cover and intermediate members are raised the hook 28 moves out from under the intermediate member thereby releasing the same due to the relative positions of the pivots of the cover and intermediate members.

For the purpose of moving intermediate member 25 to the desired position, and for maintaining it therein, I have provided a pair of cams 29 integral with cover 14', each having a steep portion 29^a. Each cam 29 is engaged by a follower 30 forming an extension of each finger 27 of the intermediate member 25. When, now, the cover 14' is lifted from its closed position, intermediate member 25 will be lifted due to the hook 28 of cover 14'. At the same time, follower 30 will be acted upon by steep portion 29^a of the cam which action will be effective independently of hook 28 to raise the intermediate member 25 until follower 30 has ridden past steep portion 29^a. Intermediate member 25 will now occupy the position shown

in dotted lines in Fig. 7. Further movement of the cover 14' will no longer move intermediate member upward, since the middle portion of cam 29 is concentric with pivot 16' of cover 14'. At the same time intermediate member 25 cannot be moved materially past the position shown in dotted lines in Fig. 4 due to accidental causes, since a portion of the fingers 30 will strike against base member 15'. 75

It will be understood that other arrangements of cams for actuating the intermediate member 25 may be used. Thus the intermediate member may be caused to assume a lowered position against the base member 80 when cover 14' is in a fully opened position if this is desired.

The operation of this form of my device is essentially the same as that of the form first described. The use of the device, however, is facilitated by the operation of the intermediate member which thus prevents the loose ends of the lace from escaping while the cover member is being closed. As clearly shown in Figure 6, the upstanding 85 portions or ears 17' fulfill the same function as extending portions 23, 23 of the form of device shown in Figs. 1 and 2 to prevent the laces being carried below the effective gripping areas of members 18' and 19'. 90

In Fig. 4 I have shown conventional means for attaching the clasp to the shoe tongue in the form of a prong 13'. I may, however, provide means for engaging the shoe tongue which shall be capable of automatic release 100 whereby the clasp may be removed from the shoe without the necessity of unbending the portion of the prong or prongs beneath the shoe tongue. In Figs. 8, 9 and 10 I have shown this automatic means in connection 105 with the other improved features which have already been described, but it will be evident that the releasing means may be incorporated without the inclusion of the intermediate member, should this be desired. 110

Referring now to Fig. 8, I have provided a presser member 35 which has a spring body portion 36 secured to base member 15'' by means of a rivet 37 or other attaching means. Spring portion 36 urges the presser member 35, the under side of which preferably is corrugated as shown, against an opposing member 38, which may also be corrugated and attached to and forming an extension of base member 15''. A slot 39 is 115 provided in tongue 11'' for the insertion or removal of the opposing member 38. As shown in Figs. 8, 9 and 10, body portion 36 of the presser member is provided with a cut out portion 36^a to accommodate upstanding or gripping member 19'', and with an upstanding hook-shape member 40, gripping member 19'' being undercut as shown by the dotted lines of Fig. 10. As shown in this figure cut out portion or slot 36^a is long 120

enough for member 36 to be slipped over member 19" in a cross-wise position. Member 40 enters a slot 41 in cover 14" and is engaged by the end 42 of the slot when the cover is in a fully raised position. Thus continued movement of cover 14" past a fully open position causes engagement of the end 42 of the slot 41 with the hook member 40 to lift the latter and hence the presser member 35 against spring 36 thereby releasing the clasp from the tongue and permitting the clasp to be removed by withdrawing opposing member 38 through slot 39 in the tongue. Otherwise the method of using this form of my improved device is identical with the form already described and illustrated in Figs. 4 to 7 inclusive.

It will thus be seen that where simplicity of manufacture is paramount, the form illustrated in Figs. 1 to 3 inclusive may be used, while on the other hand, I have provided relatively simple and practical means for facilitating the operation of the device and for accomplishing its ready removal from the shoe when it is desirable to employ the features illustrated in Figs. 4 to 10 inclusive.

An important advantage of my invention arises from the fact that it may be secured to the shoe tongue. It is a matter of common experience that inevitably the tongue of a shoe will in time tend to work to one side of the shoe thereby impairing its neat appearance. By the use of my device however, it will be seen that when the laces have been gripped thereby the tongue will be held securely in its proper place and all possibility of the tongue being gradually worked to one side of the shoe is prevented.

While I have described in great detail embodiments of these different forms, as required by the patent statutes, it will be understood that such forms are illustrative only and that the invention may be carried out in various other specific embodiments. Moreover, as will readily be apparent, certain features of one or the other modifications may be omitted, and some may be altered and embodied in others and the general objects of the invention accomplished.

In the foregoing description and in the claims the terms "semi-open" and "semi-closed" are to be construed in a general rather than a mathematical sense as the "semi-open" (or semi-closed) position referred to need not be exactly half way between the fully closed and fully open positions but may be any intermediate position as may prove desirable in practice.

I claim:

1. A clasp for shoe strings comprising in combination, a base member, a cover member pivoted thereto, an upstanding member carried by said base member and a cam-shaped member attached to said cover member and coacting with said upstanding mem-

ber to bind the laces therebetween while the cover member is moved from a semi-open to a closed position.

2. A clasp for shoe strings comprising in combination, a base member, a cover member, means actuated by movement of said cover member for gripping the laces, and a pivoted intermediate member between said cover and base members adapted to form with said cover member a housing for the loose ends of the laces while said cover member is in a semi-open position.

3. A clasp for shoe strings comprising in combination, a base member, a cover member, means actuated by movement of said cover member for gripping the laces and a pivoted intermediate member between said cover and base members, means for holding said intermediate member in a raised position when said cover is in an open position whereby in such positions of cover and intermediate members the ends of the laces may be slipped between them, said holding means permitting said intermediate member to return to the closed position with said cover member.

4. A clasp for shoe strings comprising in combination, a base member, a cover member, means actuated by movement of said cover member for gripping the laces and a pivoted intermediate member between said cover and base members, means for holding said intermediate member in a raised position when said cover is in an open position whereby in such positions of cover and intermediate members the ends of the laces may be slipped between them, said means last mentioned permitting said cover member to close against said intermediate member upon further movement of the cover member while said intermediate member is in a raised position and permitting said intermediate member to return to the closed position with said cover member.

5. A clasp for shoe strings comprising in combination, a base member, a cover member, means actuated by movement of said cover member for gripping the laces and a pivoted intermediate member between said cover and base members, means for holding said intermediate member in a raised position when said cover is in an open position whereby in such positions of cover and intermediate members the ends of the laces may be slipped between them, said holding means permitting said intermediate member to return to the closed position with said cover member, said cover member having a hook shaped portion adapted to engage the under side of the intermediate member prior to said cover member attaining a closed position.

6. A clasp for shoe strings comprising in combination, a base member, a cover member, means actuated by movement of said

- cover member for gripping the laces, and a pivoted intermediate member between said cover and base members, means for lifting said intermediate member with said cover member from closed position, and cam means for fixing said intermediate member in a semi-open position while said cover is moved to a fully open position.
7. A clasp for shoe strings comprising in combination, a base member, a cover member, means actuated by movement of said cover member for gripping the laces, and a pivoted intermediate member between said cover and base members, means including a cam, for lifting said intermediate member with said cover member from closed position, and cam means for fixing said intermediate member in a semi-open position while said cover is moved to a fully open position.
- 20 8. A clasp for shoe strings comprising in combination, a base member, a cover member, means actuated by movement of said cover member for gripping the laces, means for securing said clasp to a member of the shoe and means for releasing said securing means.
- 35 9. A clasp for shoe strings comprising in combination, a base member, a cover member, means actuated by movement of said cover member for gripping the laces, means comprising a spring pressed presser-member for securing said clasp to a member of the shoe and means for releasing said securing means.
- 50 10. A clasp for shoe strings comprising in combination, a base member, a cover member pivoted thereto, opposing gripping members for said shoe strings respectively carried by said cover and base members and constructed and arranged to grip said laces while said cover member is moved from a semi-open to a closed position, means for securing said clasp to a member of the shoe and means actuated by movement of said cover member for releasing said securing means.
- 55 11. A clasp for shoe strings comprising in combination, a base member, a cover member, means actuated by movement of said cover member for gripping the laces and a pivoted intermediate member between said cover and base members, means for holding said intermediate member in a raised position when said cover is in an open position whereby in such positions of cover and intermediate members the ends of the laces may be slipped between them, said holding means permitting said intermediate member to return to the closed position with said cover member, means for securing said clasp to a member of the shoe and means actuated by movement of said member for releasing said securing means.
- 60 12. In combination with a lace shoe having a tongue, a clasp having a base member and a cover member, means actuated by movement of said cover member for gripping the laces, means for securing said clasp to said tongue and means actuated by movement of the cover member for releasing said securing means.
- 65 13. In combination with a lace shoe having a tongue, a clasp having a base member and a cover member, means actuated by movement of said cover member for gripping the laces, means for securing such clasp to said tongue and means for releasing said securing means.
- 75 14. In combination with a laced shoe having a tongue, a clasp having a base member and a cover member, means actuated by movements of said cover member for gripping the laces, and means for securing such clasp to said tongue.

BORIS B. HOPPE.
